UNITED STATES PATENT OFFICE

ROGER BRAUNSTEIN, OF PARIS, FRANCE, ASSIGNOR TO SOCIÉTÉ ANONYME DES ANCIENS ÉTABLISSEMENTS BRAUNSTEIN FRÉRES, OF PARIS, FRANCE

MACHINE FOR INTERFOLDING SHEETS OF CIGARETTE PAPERS

Application filed June 27, 1927, Serial No. 201,867, and in France July 6, 1926.

The present invention has for its subject a machine for interfolding the sheets of cigarette paper, which is characterized by its arrangement as a whole and by the provision of auxiliary devices.

5 The sheets of paper are engaged between two conveying bands which hold them in their folded condition and convey them in front of interfolding wheels. Conveying levers acting by suction remove the sheets from between the conveying bands and pass them in their final condition into the tooth spaces of the interfolding wheels.

10 In this machine it is necessary for the continuous web unwound from the spool to be folded in the direction of the length by a special device, then cut into suitable lengths, then fed into the teeth of interfolding wheels without being left free at any moment, but 15 being, on the contrary, always conducted during the whole of its course by devices which hold it and prevent it from being carried away by the least blast of air as is the case in the majority of machines actually in existence.

20 The device for counting and separating in packets is characterized by the fact that, after every sixty sheets, for example, the sheet which is opposite one of the interfolding 25 wheels instead of being introduced into this wheel is held automatically by a suitable device in such a manner that a gap is formed in the interfolding, which gap can be found very easily in the pile of interfolded sheets 30 collected in the magazine of the machine.

35 The invention will now be described with reference to the accompanying drawings wherein:

40 Figure 1 is a side elevation of an interfolding machine in accordance with the present invention.

Figure 2 is an end view of the retaining device which conducts the sheets, by means of suction from the conveying bands to the 45 interfolding wheels,

Figure 3 is a perspective view, somewhat diagrammatic showing the interfolding wheels,

50 Figure 4 shows in section the folding device.

This machine is of the type comprising groups of two interfolding wheels such as are described in United States Patent No. 1,502,333, granted in the name of the present applicant. These wheels include teeth between which the sheets of paper are introduced; in their rotation the teeth of the two wheels come in mesh in such a manner that the sheets of paper are interfolded.

55 Referring to Figure 1 a separate web of paper is supplied for each interfolding wheel, which web is unwound under constant tension by means of a brake device known per se and not illustrated in the drawings. The web of paper is then folded longitudinally 60 along the middle by passing through a kind of slot or channel 3 and the web, thus folded longitudinally, then passes into the cutter device 4.

65 Beyond the cutter device is placed a conveying device provided with a lower conveying band 5 and an upper conveying band 6, these two bands moving in a direction such that the adjacent runs have imparted thereto movements of the same speed and in the same 70 direction.

75 The upper band 6 is shorter than the lower band 5 by a length equal to or greater than the length of a sheet.

These two bands do not bear strongly one 80 upon the other but there is left between them a small amount of space sufficient to enable the sheet of paper to be withdrawn without tearing.

85 Beyond this conveying device is placed a retaining member for the sheets formed by a series of suction pipes 7 (Figures 2 and 3) oscillating between the conveying devices and the corresponding interfolding wheels 30. The wheels 30 are of the type constituting the 90 subject matter of United States Patent 1,502,333.

95 These suction pipes are formed by hollow tubes and communicate internally with a source of suction and their ends are adapted to engage with the sheet of paper and carry it, without it being liable of falling off, to the teeth of the interfolding wheel which is adapted to receive it.

100 The suction pipes 7 are mounted on a tubu-

lar sleeve 8 which is rocked by means of a lever 9 to which it is secured and which carries a roller 10 co-operating with a cam 11 against which said roller is pressed by a tension spring 12.

The pipes 7 are preferably mounted detachably on the hollow sleeve 8, and the arrangement illustrated in the drawings, which is particularly simple, gives good results in practice. The pipes 7 are provided at their lower ends with a truncated tip 27 which may be fitted into a socket of corresponding shape provided in the sleeve 8. A spring formed by an arcuate leaf 29 holds the pipe in position in its socket by simple pressure. In the case of stoppage the pipes can be removed readily and immediately and tested.

A roller 18, preferably provided with a material having a high coefficient of friction such as rubber, is supported by a lever 19 capable of oscillating about a shaft 20 mounted upon the frame 4 of the machine.

This lever 19 has secured to it a lever 21 having the same pivot and of which the end is formed by an angular stop 25 bearing upon a cam 22 and under the action of a spring 23.

The cam 22 is provided with a notch 24 into which the stop 25 of the lever 21 falls suddenly once per revolution. It will thus be seen that at regular intervals the roller 18 is pressed against the conveying band 5 and the sheet brought between the roller 18 and this conveying band, instead of being engaged by the suction device, and conducted to the interlocking wheel 30, is discharged directly into a suitable container 26 in such a manner that one of the sheets is withdrawn, at regular intervals, from the interlocking cycle.

Any suitable registering mechanism may be employed as the counting means and actuated from the shaft upon which the cam 22 is mounted or through the movement of the lever 21.

Having now particularly described and ascertained the nature of my said invention and in what manner the same is to be performed, I declare that what I claim is:

1. A machine for interlocking sheets of cigarette paper in which the paper is supplied in the form of a continuous web, comprising means for folding the web longitudinally before cutting, means for cutting the folded web into sheets of suitable length, toothed interlocking wheels for receiving the cut sheets, upper and lower conveying bands between which the sheets are conveyed from the cutting means to the interlocking wheels, a suction device by which the sheets are withdrawn from between the conveying bands and placed into the toothed spaces of the interlocking wheels, the several elements being so arranged as to positively control the paper through the conveying and manipulative steps, so that at no moment is it left to itself during its passage through the machine.

2. A machine according to claim 1 comprising a roller located above the lower conveying band, a system of levers controlling the height of said roller above said lower band and a cam cooperating with said system of levers for depressing said roller at intervals against said lower conveying band.

Signed at Paris this 15th of June 1927.
ROGER BRAUNSTEIN.
